UNITED STATES PATENT OFFICE

99,418

DESIGN FOR A KEY HOLDER

Otto P. Schaller, Cranston, R. I.

Application March 12, 1936, Serial No. 61,589

Term of patent 3½ years

To all whom it may concern:

Be it known that I, Otto P. Schaller, a citizen of Germany, residing in the city of Cranston, county of Providence, State of Rhode Island, have invented a new, original, and ornametal Design for a Key Holder, of which the following is a specification, reference being had to the accompanying drawing, forming a part thereof.

Fig. 1 is a side view of a key holder positioned in a horizontal plane, showing my new design; Fig. 2 is a top view; Fig. 3 is a bottom view; and Fig. 4 is an end view of the same.

I claim:

The ornamental design for a key holder, substantially as shown.

OTTO P. SCHALLER.
